(57) **CLAIM**

The ornamental design for a paper towel holder for countertop, as shown and described.

DESCRIPTION

FIG. 1 is a front perspective view of a paper towel holder for countertop, showing my new design;

FIG. 2 is rear perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof; and,

FIG. 8 is a partial enlarged view according to the broken square shown in FIG. 1.
